UNITED STATES PATENT OFFICE.

JAMES A. BROOKS, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

CAR-TRUCK.

1,071,694.

Specification of Letters Patent. Patented Sept. 2, 1913.

Application filed June 7, 1912. Serial No. 702,143.

To all whom it may concern:

Be it known that I, JAMES A. BROOKS, a citizen of the United States, residing in the city of Philadelphia, county of Philadelphia, and State of Pennsylvania, and whose post-office address is care of The J. G. Brill Co., Sixty-second street and Woodland avenue, in said city, have invented certain new and useful Improvements in Car-Trucks, of which the following is a specification.

My invention has relation to improvements in car trucks, more especially those adapted for use in connection with electric motors, and in the brake-mechanism therefor; and the special object of my invention is to adapt trucks of the class known as the "Master Car Builders' standard" for use in connection with street railways; to generally strengthen and economize in their construction; and to render them easy riding under high speeds. To this end, my improvements have been directed to the devices for suspending or supporting the truck bolster, whereby a low hung bolster resulting in a low center of gravity for the supported car body is secured; and to the general improvement in the bolster construction and parts of the truck immediately related thereto.

My invention, therefore, resides in the combination of parts and details of construction hereinafter described and finally pointed out in the claims appended hereto.

I have in the drawing appended hereto, in which like reference characters indicate corresponding parts throughout the several views, shown several embodiments of my invention, in which—

Figure 1 is a side elevation of a car truck embodying my improvements. Fig. 2 is an enlarged plan view of a portion of the truck adjacent one wheel and one end of the bolster. Fig. 3 is a side elevation partly in section, the section being taken substantially on the line $a-a$ of Fig. 2 looking in the direction of the arrows. Fig. 4 is an enlarged sectional elevation showing a portion of the transom, swing and spring links and bolster-spring support, the section being taken substantially on the line $b-b$ of Fig. 2 looking in the direction of the arrows. Fig. 4^a is an enlarged section through the lower end of the hangers and the seat for the bolster

spring. Fig. 4^b is a section of Fig. 4^a on the line 4^b—4^b looking in the direction of the arrows. Fig. 5 is a side elevation of a portion of the truck frame, showing a modified form of bolster support. Fig. 6 is a sectional elevation substantially in the plane of the line $c-c$ looking generally in the direction of the arrows. Fig. 7 is an enlarged sectional elevation of the upper end of the support for the swing links, the section being taken substantially on the line $d-d$ of Fig. 6, looking in the direction of the arrows. Fig. 7^a shows respectively an end and side elevation of the bearing of Fig. 7. Fig. 7^b shows respectively end, side and plan views of the bearing block of the construction shown in Fig. 7. Fig. 8 is an end elevation, partly in section, of another modified form of construction, the section being taken substantially on the line $e-e$ of Fig. 9, looking in the general direction of the arrows. Fig. 9 is a side elevation, partly in section, of Fig. 8. Fig. 10 is a side elevation, partly in section, showing the essential portions of my improved brake mechanism. Fig. 11 is an enlarged sectional elevation of the spring bearing block showing the connection of the release spring and the connecting rod thereto; and Fig. 12 is a like view of a modification of the connection.

I will first describe my improvements in connection with the construction shown in Figs. 1, 2, 3, and 4 inclusive.

The truck in its general construction forms no part of my present invention and may be varied to suit special requirements and only so much of it as is essential to the application and my improvements will be described.

At 1 are the car wheels, 2 are the axles.

At 3 are the side frames, deflected downward centrally as at 4 to provide a low support for the bolster, and having axle box pedestals 5 from which extend the arms 7. These arms are connected transversely by cross bars 8 thus forming a rectangular truck frame.

At 9 are the usual equalizing bars, which are spaced apart and located below the plane of the side frames, and which are of the usual gooseneck form, the ends 10 of which are seated in cavities 11 formed in the top of the axle boxes 12.

At 13 are the equalizer-bar springs, which

are seated upon the equalizing bars 9 and bear against castings 14 secured to the side frames, respectively.

At 15 are the transoms, which are secured together by the stay plates 16, and at their ends to the section 4 of the side bars by plates 17 and 18, and additionally by the gusset plates 19, which have their down-turned ends 20 bolted to the section 4 of the side bars. The bolster chafing plates 21 are secured to the transoms in the conventional way. The truck frame may have pedestal tie-bars 22, and a lower cord 23 secured to ears 24 on the under arms of the pedestals 5.

The construction thus far described may be, as above suggested, of any form suitable to carrying out the improvements, which I shall now describe with particularity.

The bolster construction.—Where duplication of parts is essential, it will be assumed that they are described, one side of the truck only being shown. As the sub-bolster or sand-plank sustains no weight the bolster springs being supported directly upon the swing links as will be hereinafter described, it is only necessary to tie the spring seats together, transversely so as to cause them to work in unison. For this purpose, I employ a flat plate or bar 25. This plate is riveted or otherwise appropriately and securely fixed to the inner end 25^a of a spring-seat bearing-block marked generally 26, consisting of a casting having a top plate 27, a pendant lateral channel 28 and pendant strengthening webs 29, 30. This bearing block 26 carries a spring-seat comprising a substantially rectangular casting generally marked 31, consisting of the rectangular and elevated portion 32 in the top of which is formed a recess 33 and the flanges 34 which latter are bolted or riveted to the top plate 27 of the bearing-block 26. As the foregoing construction is the same at both ends of the bar 26, the description of one end will suffice.

Upon each of the spring-seats 31 are seated the elliptic bolster springs 35, the band 36 of which is placed directly within the recess 33 which restrains the springs from lateral displacement. The upper portion of these springs extend upwardly between the transoms 15 and are secured to the bolster marked generally 37 in any appropriate manner. As the construction of the bolster forms no part of my present invention, it may be built up as desired, its present function being merely to efficiently support the car body and to transversely tie or connect the two bolster springs (or sets) together. The bolster is provided with a center-pivot construction 38 of any desired type, bolster chafing plates 39 and side bearings 40 of the usual or desired construction. By reason 65 of the depression of the intermediate por-

tion of the side bars, the whole bolster construction is hung low, thereby producing a very low center of gravity, allowing the car body bolster to lie well within the upper plane of the wheels of the truck and affording easy access and exit to or from the car. To aid in bringing about this result, I employ pairs of swing and spring links, generally marked 41. These links, which are splayed outwardly as shown in Fig. 3, each comprise an eye-bolt 42 screw threaded on their upper ends at 43 to adjustably take the spring cap 44, the lower ends of the eye-bolt each having an apertured enlargement or eye 45, which forms a bearing for tie rods 46, which pass through the eyes, the outer ends of the tie rods being provided with cotter pins 47. The bearing blocks 26 rest directly on the tie rods 46 and there may be a rotative movement between those two parts, the sides of the channel 28 preventing lateral displacement between the parts, while allowing of this movement, and the opening of the channel permitting the ready removal of the cross bar 25 and its associated parts from the links, the weight carried by the bolster being sufficient to keep the parts together with a working engagement. The side webs 30 of the bearing block 26 engage the inner sides of the eyes 45 of the eye-bolt 42, so as to preserve them at the proper distance apart.

The transoms are each provided with inverted angle-irons 48, the upper webs 49 of which are bolted to the flange 50 of the transoms 15, as shown in Fig. 4, by bolts 51, some of which pass through the flange of the chafing plate 21 and through the gusset plates 19, thereby providing a short channel for the support of the upper end of the swing-links from the transoms.

At 52 are the link pins. These consist of a bolt, headed at 53, the head being set into the sides of the transoms 15, and pass through an aperture formed therein and likewise through an aperture in the web 54 of the plate 48, and a nut 55. Each of the swing links 41 are provided with yokes marked generally 56, the upper ends provided with apertured eyes or enlargements 57 of a width substantially the distance between the transoms 15 and the web 54 of the brackets 48; and in the apertures of its eyes 57 are inserted bushings 58, and through the bushings the bolt 52 passes. The lower ends of the yokes 56 are enlarged to form spring-seats 59, at the center of which are hubs 60, having apertures 61, through which the shank of the eye-bolts 42 loosely pass. The link springs 62 are seated on the spring-seats 59 and the caps 44 rest thereon. In this way, the bolster is pivotally hung from the transoms by paired links, allowing the bolster to swing laterally of the truck and additional spring supports in the suspend- 125 130

ing links provided, the links being capable of extension in the direction of their length, the eye-bolts and spring caps being capable of slight displacement out of the parallel, in order to allow for the change of position of the parts of the suspension during the transverse swing of all the parts. The parts may be readily organized or assembled, or taken apart for construction and repair; the construction resulting in an easy riding truck under high speeds in which the pivotal connections or supports have a low center of gravity.

The character and arrangement of the spring system is also of considerable importance. As shown, the springs 13 are seated near the axle boxes. The bolster-springs are out near the ends of the bolster, and the link-springs are adjacent to and practically paired with the bolster springs and at each side of the bolster springs and substantially in line with the bolster springs in the direction of their operative spring connections. In this way, the bolster is given additional spring support from the truck frame and lateral stability; and the arrangement of the springs tends to increase the easy riding qualities of the trucks.

In Figs. 5, 6, 7^a and 7^b, is shown a modified method of supporting the bolster. To the top web 50 of the transoms are secured oppositely located bearing-blocks 63, each comprising a casting 64 having ears 65 by means of which they are secured upon the transoms, and a recess 66 having inclined sides 67, one wall 68 being closed, the other wall 69 of the elevated portion being open, as at 70. In these recesses 66 are seated bearing-blocks 71 having inclined sides 72 and a circular bearing surface 73. At 74 is a link pin extending between the bearing-blocks 63, its ends passing through the openings 70 in the sides of the bearing block and seated in the bearings 71. From the link-pins 74 are pivoted hangers or links 75, the upper eyes 76 of which embrace the link-pins, so as to allow them to swing transversely of the truck, the inner faces of the eyes bearing against the shoulders or enlargements 77 on the link-pin. At 78 is a spring seat having journals 79 passing through eyes 80 formed on the lower ends of the links 75, the spring-seat having shoulders 81 which with cotter-pins 82 on the ends of the journals, confine the links in position, the spring-seats having recesses 83 in which springs 84 are placed, and which support spring-caps 85 having pendant nibs 86, in the usual manner. Upon these caps are seated the bolster-springs 35, which in turn support the bolster 37, and it in turn the riser 37^a for the side bearings 40. It will be noted in connection with this structure that the parts are compactly organized, and that the usual sand-plank or tie-bar con-

necting the bolster spring seats together is dispensed with, and a support for the bolster-springs and the end-bearings is closely located relatively to each other and to the side frames of the truck.

In the modification shown in Figs. 8 and 9, U-shaped straps 87 are oppositely secured by their bent-ends 88 to the horizontal flanges 50 of the transoms 15, the cross-bar 89 being apertured or slotted at 90 in the direction of the length of the bar to allow of the passage therethrough of the links 91, which latter are adapted to swing in said slots. The upper or threaded ends 92 of the links pass through widened apertures 93 in the spring-caps 94 located within the straps, the upper ends of the links carrying segmental nuts 95, which bear in segmental recesses 96 in the tops of the spring caps. Spiral springs 97 seated in slotted spring-seats 98 within the straps and resting on the cross-bars 89, support the spring caps. The lower ends or eyes 99 of the links 91 pivotally engage cross or tie-bars 100, and the cross bars carry a casting 101 straddling them, (the casting being of the same general construction as the block 26) the eyes of the links being held between the ends of the casting and cotter-pins 102. The inner end of the casting is secured to the tie-bar 25 in the manner before described. A spring-seat 103 is bolted to the casting 101, and on the spring seat is seated the bolster springs 35, which in turn support the end of the bolster 37 from which the side bearing riser 37^a extends, which latter supports the side bearings 40.

The brake mechanism.—The improvements herein described which improvements constitute the subject matter of another application for Letters Patent filed by me, relate more particularly to what are known as inside-hung brake shoes. The improvements are shown in Figs. 10, 11 and 12, respectively. Referring, first, to Figs. 1 and 11. The brake shoes are shown at 104, each shoe being provided with a head or carrier 105 having a bifurcated lug or projection 106, the extreme ends of which carry pins 107. At 19 are the truck gusset-plates. Underneath the gusset plates are blocks 108 to which are secured paired links or hangers 109, the lower ends of which pivotally engage bolts 110 passing through the brake heads 105. At 111 is the live lever, the upper end of which is secured to a brake rod 112 leading to the source of power and which passes through the bifurcated extension of the brake head, its lower end 113 projecting below the same. The live lever is pivoted to the brake head by the bolt 114. At 115 is the dead lever. At 116 is an upwardly extending curved bracket secured to the gusset-plates or transoms. At 117 are the paired links pivotally secured to the bracket 130

by a bolt 118. The outer ends of these links carry a bolt 119 to which is secured the upper end of the dead lever, which later passes through the bifurcated extension 106 of the brake head, it being pivoted or fulcrumed to the brake head at 120. Both live and dead levers pass through slots 19^b in the gusset plates. The lower ends 113, 121 of the live and dead levers are secured together by the turn buckle 122, comprising the sections 123 pivotally secured by bolts 124, 125 to the lower ends of the said levers, the sections being united by an oppositely threaded adjusting rod 125, which is threaded into the sections 123. Jam-nuts 127 may be used to retain adjustment in the usual way. The above arrangement organizes the brake apparatus into a convenient accessible whole. The usual release spring is dispensed with, and in its place I substitute a release spring extending between the brake head or carrier, so that the pull of the release spring will be almost direct and very positive. The release spring comprises the bolts 128 pivoted to the bolts 107 secured to the extensions 106 of the brake heads, the threaded ends 129 of the bolts engaging threaded apertures formed in spring-heads or carriers 130, the outer surfaces of which are cast or so formed as to take the turns of a spiral spring 131, which frequently engages said carriers. Shortening or elongation of this spring device may be had by turning the spring 131 or heads 130 in the appropriate direction. The connection of the bolts with the spring carriers may be modified, as in Fig. 12, by causing the threaded ends 129 to pass through enlarged holes 132 in the carriers which form a recess 40 for the reception of a nut 133 movable on the ends of the bolts, by means of which the desired adjustment can be had.

It is apparent that my various improvements can be embodied in structures specifically different from those herein disclosed without departing from the spirit of my invention.

I claim:

1. A car truck having running gear and a main frame, lateral transoms connecting side frames of the main frame brackets depending from the transoms, a lateral spring-plank or tie-bar, laterally-swinging spring-links suspended from the brackets, a pivotal connection between the said links and spring-plank, spring-seats on the spring plank bolster springs on the spring-plank, and a bolster on the bolster-springs.

2. A car truck having a frame, transoms, and running gear, a spring system comprising springs supporting the frame on and adjacent the running gear, paired and oppositely located spring-links pivotally suspended from the transoms adjacent the plane 65 of the wheels, bolster springs supported by

said paired links, a bolster supported by said bolster springs, and a pivotal and tying connection between the terminals of said links.

3. In a car truck, the combination with a truck frame and wheels, the truck frame being depressed intermediate of the wheels, lateral connections between the depressed portions of the truck frame, means for spring-supporting the truck frame, pairs of laterally swinging links carrying springs secured to said lateral connections and located approximately in line with the plane of the wheels, bolster springs supported by said links, and a bolster supported by said bolster springs and extending between them and located between said lateral connections. 70 75

4. In a car truck, the combination with a truck frame, transoms, pairs of laterally-swinging spring-links pendant from the transoms, bolster-springs supported upon bearings which are in turn supported by said links, a bolster supported upon said bolster-springs between the transoms, and means for tying the said bolster spring-bearings together. 80 85

5. In a car truck, the combination with a truck frame, transoms, pairs of laterally-swinging spring-links pendant from the transoms, bolster-springs supported upon bearings which are in turn supported by said links, a bolster supported upon said bolster-springs between the transoms, means for tying the said bolster spring bearings together, equalizing bars supported on axle 90 boxes, and springs supporting the truck frame on said equalizing bars. 95 100

6. In a car truck the combination with a truck frame, transoms, pairs of spring links pivotally supported on the transoms and pendant therefrom, a bearing pivotally supported upon the lower ends of said links, means for laterally connecting said bearings, bolster springs on said bearings, and a bolster on said bolster springs. 105 110

7. In a car truck, the combination with a truck frame, transoms, pairs of spring links pivotally supported on the transoms and pendant therefrom, a bearing pivotally supported upon the lower ends of said links, 115 means for laterally connecting said bearings, bolster springs on said bearings, a bolster on said bolster springs, equalizing bars supported on axle boxes, and springs on the equalizing bars supporting the truck frame. 120

8. In a car truck, the combination with a truck frame, laterally extending transoms spaced apart, means for supporting a bolster between the transoms comprising multi-part links having interposed springs, the links being supported in pairs opposite each other by a pivotal connection at the top with the transoms, a pivotal transverse connection between each of the pairs of links at the bottom, a spring support on said transverse 125 130

connection, bolster springs on said support and a bolster on said springs.

9. In a car truck, the combination with transoms, of oppositely disposed channelled housings formed on the transoms, pivot pins extending laterally through said housings, multi-part links having interposed springs comprising a yoke held within the housing through which said pivot pin passes, and a lower spring-supported bolt having an eye, a pivot pin extending through said eyes and connecting the links in pairs, and a spring seat on said latter pivot pin.

10. In a car truck, the combination with swing links pivotally supported from the truck frame, a pivot pin pairing said links, a casting removably supported on said pivot pin, and an elevated spring seat supported on said casting and having a spring receiving recess in its top.

11. In a car truck, the combination with a truck frame, of links pivotally supported from the truck frame, said links being united in pairs by a pivot pin, a casting removably supported on each of the pivot pins, a bar connecting said castings, an elevated spring seat supported on said casting having a spring-receiving recess in its top, springs seated in said recess, and a bolster on said springs.

12. A pivot bearing block for a car truck comprising a casting having a recess, an opening in one side of the casting alining with the recess, a bearing block having an upper and open bearing surface located with said recess.

13. A pivot bearing block comprising a casting having a recess with upwardly in-

clined opposite walls, and a bearing block having inclined side walls and a bearing surface in the top seated in the recess.

14. A bearing block comprising a casting having a wedge-shaped recess with inclosing walls, one wall being open at the side, and a wedge-shaped bearing block seated within said recess and having a bearing surface alining with the said wall opening.

15. A link spring-bearing, comprising a spring-seat-bearing block having a lateral groove or recess 28 on its under side, a spring seat 31 having lugs 34 resting on and secured to the spring-seat bearing-block and having an upwardly extending portion 32 the top of which is recessed to receive a spring.

16. A tie bar 25 having spring-seat bearing-blocks 26 secured at its ends, channels 28 formed laterally on the under side of the said bearing block, and elevated spring seats 31 having flanges 34 secured on top of the said bearing blocks.

17. In a car truck, the combination with transoms, a stirrup secured to the transoms, a spring within the stirrup, a cap on said spring, a bolt passing loosely through said cap, spring and stirrup, and pendant from the cap a spherical bearing supporting the bolt on the cap, and means secured to the end of the bolt for supporting a spring.

Signed at the city of Philadelphia, county of Philadelphia and State of Pennsylvania, this 4th day of June, 1912.

JAMES A. BROOKS.
